UNITED STATES PATENT OFFICE.

JOSEPHINE L. MACAVOY, OF BUCKHANNON, WEST VIRGINIA.

CARRIER FOR PHOTOGRAPHIC BACKGROUNDS.

1,412,697.

Specification of Letters Patent. Patented Apr. 11, 1922.

Application filed December 17, 1921. Serial No. 523,098.

To all whom it may concern:

Be it known that I, JOSEPHINE L. MACAVOY, a citizen of the United States, residing at Buckhannon, in the county of Upshur and 5 State of West Virginia, have invented new and useful Improvements in Carriers for Photographic Backgrounds, of which the following is a specification.

This invention relates to carriers for 10 photographic backgrounds and has for its principal object the provision of a portable and knockdown carrier adapted for the selective display of any one of a plurality of backgrounds which may be arranged on 15 self-raising rollers, and to the arrangement in a series of planes, extending in a depth direction, of means for supporting actual draperies or curtains which may likewise be selectively utilized either singly or in 20 any order of combination.

Other objects will appear as the description proceeds.

The invention will first be hereinafter described in connection with the accompanying 25 drawings, which constitute part of this specification, and then more specifically defined in the claims at the end of the description.

In the accompanying drawings, wherein 30 similar reference characters are used to designate corresponding parts throughout the several views:—

Figure 1 is a perspective view showing the carrier with the dust canopy raised 35 above its normal position.

Figure 2 is a detailed front view of one of the end standards.

Figure 3 is an end view in cross section of the carrier.

40 Figure 4 is a detailed view of the rod which joins the end standards at the base.

Figures 5 and 6 are detail views of the transverse rods carried at the upper ends of the end standards.

45 Referring in detail to the several figures the numeral 1 represents my improved carrier for photographic backgrounds which comprises two end standards 2 and 3 each of which is joined at its base to a trans- 50 verse member 4 by means of a threaded coupling 5. Each of the standards is braced in a vertical position from the transverse member 4 by means of the inclined braces 6 which are riveted or bolted thereto and 55 to the opposite ends of the said transverse

members. Elbow couplings 7 are threaded to the outer ends of the transverse members, pointing downward, and are fitted with suitable castors 8. The standards 2 and 3 are connected at the base by the rod 9 which 60 is provided with right and left hand threads at its respective ends 10 and 11 as shown in Figure 4 by means of which it may be simultaneously screwed into sockets 12 and 13 which are formed on the couplings 5. At 65 the top each standard is provided with a T coupling 14, a slight distance below its upper end, and said T couplings are connected to the ends of the rod 15 which is of the same length as the rod 9 and similarly 70 provided at its ends with right and left hand screw-threads.

Removably securable to the extreme upper ends of the standards 2 and 3 is a frame 16 comprising transverse members 17 and 18 75 and longitudinal members 19 and 20 connected together by pipe couplings 21 to form a rectangular construction. Midway of their ends the transverse members 17 and 18 are provided with T couplings 22 having 80 the threads reamed away from the lower openings thereof in order that said T couplings will fit down freely over the upper ends of the standards 2 and 3. A set-screw 23 is provided for each T coupling so that 85 when the frame 16 is in place on top of the standards 2 and 3 the set-screws may be tightened and the frame held rigidly in place.

A dust canopy 24, which is rectangular in 90 shape and has downwardly extending sides 25 and 26, is provided, which in its normal position rests down upon the frame 16.

The structure thus far described is readily demountable and may be packed flat when 95 not in use. To take it apart it is only necessary to raise and remove the dust canopy loosen the set-screws 23 and remove the frame from the standards and turn the rods 15 and 9 by hand in a direction to simultaneously unthread the ends thereof from the couplings with which they are connected. The two standards, the two rods 15 and 19 and the frame may then if desired be laid away one upon another in a package having 100 105 but a few inches of thickness.

The transverse member 17 is provided on its inner side with a plurality of round holes and the transverse member 18 on its inner side with corresponding notches, said 110

holes and notches being adapted to function with the opposite ends of rollers 27 of the ordinary spring winding type. In the present case provision is made for four 5 such rollers, on each of which may be mounted a sheet 28 of scenery or other background which may be selectively pulled down into view or withdrawn from the field of view by the spring rollers.

10 The rods 15, 19 and 20 provide means on which may be hung curtains, lattice or other forms of actual drapery 29 and for this purpose said rods are provided as shown in Figures 1 and 3 with curtain rings 30 or other 15 slideable curtain fasteners. This construction makes available the use of a plurality of actual draperies in planes lying in a depth direction with reference to a camera placed in front of the carrier, and the selective use in combination therewith of any 20 one of a plurality of backgrounds painted on a single plane surface.

Not only is the device herein described advantageous from its mechanical simplicity 25 and convenience of storage but from the opportunity which it affords to obtain realistic effects in the arrangement of backgrounds.

Obviously, changes in the details of construction may be made without departing 30 from the spirit of the invention and I do not wish to limit myself to any particular form or arrangement of parts.

Having described my invention what I claim as new and desire to secure by Letters Patent, is:—

1. A carrier for photographic backgrounds comprising a frame, a plurality of rotatable and stationary members supported by said frame in parallelism in a depth direction, background material adjustable in a height direction and background material 40 slideable in a width direction carried by said rotatable and stationary members respectively.

45 2. A carrier for photographic backgrounds comprising a rectangular frame having longitudinal rods connected at their ends by transverse members, one of said members being provided with notches and 50 the other with bearing apertures corresponding in number and position with said notches, said bearing apertures and notches being for the support of spring rollers, and said rods being for the support of drapery.

55 3. A carrier for photographic backgrounds comprising a rectangular frame having longitudinal rods connected at their ends by transverse members, one of said transverse members being provided with a 60 plurality of notches for engaging the spring ends of spring rollers, the other of said transverse members being provided with a plurality of bearing apertures for journaling the opposite ends of said spring rollers, 65 T couplings secured to said transverse mem-

bers intermediate their ends and vertical standards upon which said T couplings are supported.

4. A carrier for photographic backgrounds comprising a rectangular frame 70 having longitudinal rods connected at their ends by transverse members, one of said transverse members being provided with a plurality of notches for engaging the spring ends of spring rollers the other of said transverse members being provided with a plurality of bearing apertures for journaling the opposite ends of said spring rollers, T couplings secured to said transverse members intermediate their ends, vertical standards upon which said T couplings are supported and means for securing said T couplings upon said standards.

5. A carrier for photographic backgrounds comprising a rectangular frame having longitudinal rods connected at their ends by transverse members, one of said members being provided with notches for engaging the spring ends of said spring rollers, the other of said transverse members being provided with bearing apertures for journaling the other ends of said spring rollers, T couplings arranged intermediate the ends of said transverse members, said T couplings arranged on standards by which said frame 95 is supported, and a dust canopy resting upon and fitting over said rectangular frame.

6. A carrier for photographic backgrounds comprising a pair of transverse members connected intermediate their ends by a longitudinal member, a pair of vertical standards carried by said transverse members and connected near their upper ends by a longitudinal member, a rectangular frame supported upon the upper ends of said standards, said frame comprising longitudinal rods connected at their ends by transverse members, one of said transverse members being provided with notches for engaging the spring ends of spring rollers and the other of said transverse members being provided with bearing apertures for journaling the other ends of said spring rollers, T couplings arranged intermediate the ends of said transverse members, said pipe couplings telescoping 105 upon the upper ends of said standards.

7. A carrier for photographic backgrounds comprising a pair of transverse base members connected intermediate their ends by a longitudinal member, a pair of vertical standards carried by said transverse base members and connected near their upper ends by a second longitudinal member, a rectangular frame supported upon the upper ends of said standards, said frame comprising longitudinal rods connected at their ends by upper transverse members, one of said upper transverse members being provided with notches for engaging the spring ends of spring rollers and the other of said upper 110 120 125 130 standards.

transverse members being provided with bearing apertures for journaling the other ends of said spring rollers, T couplings arranged intermediate the ends of said upper 5 transverse members, said pipe couplings telescoping upon the upper ends of said standards, and set-screws for retaining said pipe couplings in place.

8. A carrier for photographic backgrounds 10 including end sections each comprising a transverse base member and a vertical standard secured at right angles thereto intermediate the ends of said base member, said end sections being provided adjacent their 15 upper and lower ends with inwardly facing threaded sockets, means for connecting said end sections comprising rods each having right and left hand threads at its respective ends, said rods cooperating with said sockets.

20 9. A carrier for photographic backgrounds including end sections each comprising a transverse base member and a vertical standard secured at right angles thereto intermediate the ends of said base member, said end 25 sections being provided adjacent their upper

and lower ends with inwardly facing threaded sockets, means for connecting said end sections comprising rods each having right and left hand threads at its respective ends, said rods cooperating with said sockets, and 30 a rectangular frame carried by the upper ends of said end sections, said frame having longitudinal rods connected at their ends by upper transverse members, one of said upper transverse members being provided with 35 slots for engaging the spring ends of spring rollers, the other of said upper transverse members being provided with bearing apertures for journaling the other ends of said spring rollers, the longitudinal rods of said 40 frame and the upper one of said connecting rods being adapted to support drapery, and a dust canopy covering said frame.

In testimony whereof I have hereunto set my hand in presence of two subscribing witnesses.

JOSEPHINE L. MACAVOY.
